UNITED STATES PATENT OFFICE.

VINTON E. SISSON, OF CHICAGO, ILLINOIS, ASSIGNOR TO WALTER P. MURPHY, OF NEW YORK, N. Y.

METAL REINFORCEMENT FOR THE WOODEN END WALL OF A RAILWAY BOX CAR.

Application filed July 30, 1920. Serial No. 400,099.

To all whom it may concern:

Be it known that I, VINTON E. SISSON, a citizen of the United States, residing at Chicago, in the county of Cook and State 5 of Illinois, have invented certain new and useful Improvements in Metal Reenforcements for the Wooden End Wall of a Railway Box Car, of which the following is a specification.

My invention relates to the reenforcement of the wooden end walls of railway box cars, either at the time the cars are built or subsequently in the repair of the same; and the invention is concerned especially with the improvements, in certain important respects, of the type of end reenforcement now in common use which comprises a pair of vertical or substantially vertical metal members, Z-bars, for example, on the outside of the car, usually aligned with the wooden intermediate end posts of the car framing, and a bracing structure on the inside of the car to which the vertical reinforcing members are attached through the end plate, which interior bracing structure by its connection through the employment of diagonally extending struts or braces running to the side walls of the car, serves to transmit the stresses on the vertical members to the side walls of the car and with the vertical members tends to keep the superstructure of the car from the destructive strains and distortions known as weaving.

One of the objects of my present invention is to provide a more rigid and secure anchorage of the vertical reinforcing members to the end plate brace, as this portion of the interior reinforcing structure may be called, and to strengthen the latter element at the place where strength is especially required, to-wit, at the middle of the car.

A further object is to simplify and make more convenient and economical the manufacture of the end plate brace and its assembly in the car.

The invention consists of the new and improved arrangements, constructions and devices shown in the drawings and to be hereinafter described and claimed for carrying out the above stated objects and such other incidental objects as will appear in the following description of the preferred embodiment of the invention.

In the drawings, Fig. 1 is a plan view of the end of the car with the roof boards, ridge pole and purlins removed.

Fig. 2 is a fragmentary end elevation of the upper part of the car with the wooden end wall broken away to illustrate the construction of the interior reinforcing structure.

Fig. 3 is a perspective of a detail showing the connection of one of the bracing members with the end plate brace.

Fig. 4 is a perspective view of the end plate brace and the diagonal bracing members.

Fig. 5 is a perspective view of a modified form of end plate brace.

Like characters of reference designate like parts in the several figures of the drawings.

Referring to the drawings, 10 designates the outer sheathing of the end wall, 11 the side sheathing, 12 the roof, 13 the end plate, 14, 14 the side plates and 15, 15 the intermediate end posts. The car structure as described is of familiar type. On the outside of the end wall are arranged a pair of substantially upright, preferably vertical bracing members 16, aligned with the intermediate end posts 15 to which they are secured by bolts 17 through the outer sheathing, these end wall reinforcements being preferably in the form of Z-bars as shown. Within the car is a transversely arranged end plate brace which consists, in the preferred embodiment of my invention, of a pair of angle bars 18, 19 arranged so that they overlap for a distance a trifle greater than the distance between the Z-bars 16. The member 18 has its vertical flange 20 projecting upwardly from its horizontal flange 21 while the member 19 has its vertical flange 22 projecting downwardly from its horizontal flange 23. The vertical flanges lie flatwise against the inner surface of the end plate 13 and are secured thereto by bolts 24. The horizontal flanges of members 18 and 19 project inwardly and are spaced apart to receive the ends of the diagonal bracing members 25, 25 which intersect and are secured together at such intersection by a plate 26, the diagonal braces being secured to the horizontal flanges 21, 23 by rivets 27, or other suitable fastening devices. Preferably the flanges 21, 23 are

- riveted together, as shown at 28, with the interposition of a spacing plate 29 at a place midway of the overlap of members 18 and 19. The other extremities of the diagonal braces 25 are riveted to brackets 30, which latter are secured by bolts 31, or other suitable fastening devices, to the side plates 14 of the car. The upper extremities of the Z-bars 16 are bolted, or otherwise secured, in each case, to each of the two members 18 and 19 of the end plate brace, as shown at 32, 33. The end plate brace is designed to extend, preferably, across the end plate from side to side of the car and is secured at both ends to the side walls of the car. The most desirable way of making this connection is to bend the end of each of the members 18 and 19, as shown in Fig. 1 to provide a diagonal strut 34 to extend across the corner of the car and an end portion 35 which lies against the side plate and may be secured thereto by bolts 36. Any suitable means may be employed for securing the lower ends of the Z-bars 16 to the under frame of the car.
- Certain important advantages are obtained by making the end plate brace 18, 19 in two sections arranged and connected with the other parts of the reinforcing structure as shown and described. If the end plate brace be made in one piece some difficulty is experienced in bending the ends to make the attachment to the side walls of the car, which is desirable in order to utilize the end plate brace to rigidify the car structure against weaving, due to the tendency of the metal to shrink somewhat and become distorted with the changes in temperature incident to the bending operation. Moreover, by making the brace in two parts and overlapping the parts at the middle the brace is given great strength where strength is necessary, that is, at the center of the car. Besides this it is possible to obtain a very strong and rigid anchorage of the upper ends of the Z-bars, which form the exterior portion of the reinforcing structure, to the interior reenforcement. Two bolts can be used in each case, one a considerable distance above the other, one bolt attaching the Z-bar to one of the members of the end plate brace and the other to the other member. Reinforcing structures of this general character have two functions to perform. In the first place, they strengthen the end wall of the car against the thrusts and pressures of shifting cargoes. In such case the stresses against the outside reenforcement, consisting of Z-bars, are transmitted to the inner reinforcing structure and by it to the sides of the car. It is important, therefore, that the anchorage between the exterior and interior reenforcements be strong and rigid. The other function of the reenforcement is to brace the

car superstructure against the various diagonal distortions known as "weaving" to which railway box cars are subjected, due to the inertia of the upper portion of the car and the tendency of the car body to swing sidewise in rounding curves or going over rough track. In the performance of this function of the reenforcement it is equally important that rigidity be maintained between the outer and interior reinforcing structures in order that they may cooperate to keep the elements of the car framing in line.

In Fig. 5 I have illustrated a modified form of end plate brace formed of a plurality of parts for the purpose above described and providing an extended surface for the attachment of the outer vertical braces 16. This form of end plate brace comprises a pair of angle members 37 each extending toward the center of the car to a point beyond the point of attachment of the vertical bracing members 16. These angle members are secured together to form a rigid unit by means of an intermediate section 38 of angle iron to which the members 37 are riveted as will be hereinafter described. The angle member 38 is made of a length sufficient to extend beyond the points of attachment of the vertical bracing members 16 so as to overlap the members 37 and provide an extended surface as in the case of the form previously described for the attachment of the upper ends of the bracing members 16. Such extended attaching surface consists of the upwardly extending vertical flange 39 of the member 38 and the downwardly extending flanges 40 of the members 37. The diagonal bracing members 41 have the same general construction as those previously described and are connected to the end plate brace at the regions where the members 38 and 37 overlap by means of rivets or other suitable fastenings 42 which pass through the members 41 and the horizontal flanges of the members 37 and 38. The rivets 42 thus secure the braces 41 to the end plate brace and the members 37 to the member 38. The braces 41 are riveted at the region of their intersection to a plate 43, placed between the same, by means of rivets 44. It will be noted that the upper brace 41 is secured to the upper surface of the horizontal flange of the member 38 and the lower brace 41 to the lower surface of the horizontal flange of one of the members 37. The other extremities of the braces 41 are connected to the side plates by means of brackets 45 and suitable rivets and bolts in the manner already described in connection with the construction illustrated in Figs. 1 to 4 inclusive.

The form of construction shown in Fig. 5 reduces the difficulties of manufacture as described in connection with the form of

brace shown in Fig. 4 and also provides the extended surface for the attachment of the outer bracing member 16.

I claim:

1. In combination with the wooden end wall of a railway box car, a metal reenforcement for the same comprising substantially upright members on the outside of the end wall, and a transverse brace on the inside of the car composed of two members each of which extends only part way across the end of the car, the inner ends of which are arranged in overlapped relation one above the other, to the extent of more than the distance between the upright members, the upper ends of said upright members being each secured at points one above the other to both the members of said transverse brace.
2. In combination with the wooden end wall of a railway box car, a pair of substantially upright reinforcing members on the outside of the end wall, and a transverse reenforcement on the inside of the car comprising two members each of which extends only part way across the end of the car overlapped for a distance corresponding substantially to the distance between the upright members, the members of the transverse reenforcement having inwardly projecting horizontal flanges which are secured together at said overlap, and respectively upwardly and downwardly projecting webs which lie flatwise upon and are secured to the end wall of the car, the upper ends of said upright members being anchored each to both of the members of said transverse reinforcing structure.
3. In combination with the wooden end wall of a railway box car, a pair of substantially upright reinforcing members on the outside of the end wall, and a transverse reenforcement on the inside of the car comprising two members each of which extends only part way across the end of the car overlapped for a distance corresponding substantially to the distance between the upright members, the members of the transverse reenforcement having inwardly projecting horizontal flanges which are secured together at said overlap, respectively upwardly and downwardly projecting flanges which lie flatwise upon and are secured to the end wall of the car, the upper ends of said upright members being anchored each to both of the members of said transverse reinforcing structure, the outer ends of the members of said transverse reenforcement being provided with means extending diagonally across the corners of the car and secured to the side walls thereof.
4. In combination with the wooden end wall of a railway box car, a pair of substantially upright reinforcing members on the outside of the end wall, and a transverse reenforcement on the inside of the car comprising two members overlapped for a distance corresponding substantially to the distance between the upright members, the members of the transverse reenforcement having inwardly projecting horizontal flanges which are secured together at said overlap, respectively upwardly and downwardly projecting flanges which lie flatwise upon and are secured to the end wall of the car, the upper ends of said upright members being anchored each to both of the members of said transverse reinforcing structure, the outer ends of the members of said transverse reenforcement being bent so as to extend diagonally across the corners of the car and be secured to the side walls thereof.

7. In combination with the end plate and intermediate end posts of a railway car of wood construction, a pair of Z-bars on the outside of the wall aligned with and secured to said posts, an end plate reenforcement on the inside of the car consisting of two angle bars one arranged above the other with their inner ends overlapping for a distance corresponding substantially to the distance between the Z-bars, said angle bars being arranged with inwardly projecting horizontal flanges secured together for the distance of the overlap, and respectively upwardly and downwardly projecting flanges, the outer ends of said angle bars being bent so as to extend diagonally across the corners of the car with their extremities secured to the side walls thereof, and a pair of crossed bracing members each of which is secured at one end between the horizontal flanges of the angle irons at a place opposite the upper end of one of the Z-bars and at the other end to the side wall of the car at a point remote from the end wall, the upper end of each of said Z-bars being secured, through the end plate, to both of said angle bars.
8. The combination with the wooden end wall of a railway car, of a pair of substantially upright reinforcing members on the outside of the end wall, a transverse reenforcement on the inside of the car comprising a pair of angle members extending toward the center of the car end and an intermediate angle member connecting the inner ends of said angle members and overlapping the same, the vertical flanges of said angle members and said intermediate angle member lying in the same plane, the upper ends of said upright members being anchored to the vertical flanges of said angle members and intermediate angle member at the points where the same overlap, and diagonal bracing members, the ends of which are secured to the horizontal flanges of said angle members and which extend and are anchored to the side walls of the car, the outer ends of the angle members of said transverse reenforcement being bent so as to extend diagonally across the corners of the car and be secured to the side walls thereof.
9. The combination with the wooden end wall of a railway car, of a pair of substantially upright reinforcing members on the outside of the end wall, a transverse reenforcement on the inside of the car comprising a pair of angle members extending toward the center of the car end and an intermediate angle member connecting the inner ends of said angle members and overlapping the same, the vertical flanges of said angle members and said intermediate angle members lying in the same plane and the upper ends of said upright members
- being anchored to the vertical flanges of said angle members and intermediate angle member at the places where the same overlap, and diagonal bracing members, the ends of which are secured to the horizontal flanges of said angle members and which extend and are anchored to the side walls of the car.
10. The combination with the wooden end wall of a railway car, of a pair of substantially upright reinforcing members on the outside of the end wall, a transverse reenforcement on the inside of the car comprising a pair of angle members extending toward the center of the car end and an intermediate angle member connecting the inner ends of said angle members and overlapping the same, the vertical flanges of said angle members and said intermediate angle member lying in the same plane and the upper ends of said upright members being anchored to the vertical flanges, and diagonal bracing members the ends of which are secured to the horizontal flanges of said angle members and which extend and are anchored to the side walls of the car, the outer ends of said angle members of the transverse reenforcement being secured to the side walls of the car.
11. The combination with a wooden end wall of a railway car, of a pair of substantially upright reinforcing members on the outside of the end wall, a transverse reenforcement on the inside of the car comprising a pair of angle members extending toward the center of the car end and an intermediate angle member connecting the inner ends of said angle members and overlapping the same, the vertical flanges of said angle members and said intermediate angle member lying in the same plane and the upper ends of said upright members being anchored to the flange of one of said angle members in each case, and diagonal bracing members, the ends of which are secured to the horizontal flanges of said angle members and which extend and are anchored to the side walls of the car, the outer ends of the angle members of said transverse reenforcement being formed so as to extend diagonally across the corners of the car and be secured to the side walls thereof.
12. In combination with the wooden end wall of a railway box car, a metal reenforcement for the same comprising substantially upright members on the outside of the end wall, a transverse brace on the inside of the car consisting of two end members and an intermediate member overlapping the inner ends of said end members, and means for securing the upright members in each case to the overlapped ends of said end and intermediate members.
13. In combination with the wooden end wall of a railway box car, a metal reenforce-

ment for the same comprising substantially upright members on the outside of the end wall, a transverse brace on the inside of the car consisting of two end members and 5 an intermediate member overlapping the inner ends of said end members, means for securing the upright members in each case to the overlapped ends of said end and intermediate members, and means for securing 0 said transverse brace to the side walls of the car.

14. In combination with the wooden end wall of a railway box car, a metal reenforcement for the same comprising substantially 5 upright members on the outside of the end wall, a transverse brace on the inside of the car consisting of two end members extending to the side walls of the car, respectively, and an intermediate member overlapping 10 the inner ends of said end members, means for securing the upright members in each

case to the overlapped ends of said end and intermediate members and means for 25 securing said transverse brace to the side walls of the car near the corners of the car and also at places remote therefrom in each case.

15. In combination with the wooden end 30 wall of a railway box car, a metal reenforcement for the same comprising substantially upright members on the outside of the end wall, a transverse brace on the inside of the car consisting of two end members angular 35 in cross section attached to the side walls of the car, respectively, and an intermediate angle member arranged upon and overlapping and secured to the inner ends of said end members, and means for securing said 40 upright members, in each case, to the overlapped ends of said end and intermediate members.

VINTON E. SISSON.
